UNITED STATES PATENT OFFICE.

WILLIAM W. CULVER, OF ST. LOUIS, MISSOURI, ASSIGNOR TO THE WROUGHT IRON RANGE COMPANY, OF SAME PLACE.

DESIGN FOR A COOKING-RANGE.

SPECIFICATION forming part of Design No. 22,131, dated January 10, 1893.

Application filed December 10, 1892. Serial No. 454,788. Term of patent 14 years.

To all whom it may concern:

Be it known that I, WILLIAM W. CULVER, a citizen of the United States, residing at St. Louis, Missouri, have invented and produced 5 a new and original Design for Cooking-Ranges, of which the following is a specification, reference being had to the accompanying drawing, forming part thereof.

The drawing is a perspective of my design. 10 The leading feature of my design is a rectangular body portion, with a vertical back rising from the body, with a cylindrical body in front of the back, and a box like portion also in front of the back, beneath which are 15 vertical panels. At one end of the body portion is a form, beneath which is a triangular shaped surface.

Referring to the drawing, 1 represents the rectangular body portion, having a paneled front, as shown in the drawing. 20

2 is a vertical back rising from the body 1, in front of which is a cylindrical body 3, a box like portion 4, and vertical panels 5.

At one end of the body portion is a form or body 6, beneath which is a triangular shaped 25 surface 7.

What I claim is:

The design for a cooking range, substantially as herein shown and described.

WILLIAM W. CULVER.

In presence of—

ED. S. KNIGHT,
ALBERT M. EBERSOLE.
